(57) **CLAIM**

The ornamental design for a display screen with graphical user interface, as shown and described.

DESCRIPTION

FIG. 1 is a front view of a display screen with graphical user interface showing my design;

FIG. 2 is a rear view thereof;

FIG. 3 is a top view thereof;

FIG. 4 is a bottom view thereof;

FIG. 5 is a left side view thereof; and,

FIG. 6 is a right side view thereof.

The broken line showing of a portable information terminal and display screen in FIG. 1 illustrates environmental subject matter and the article of manufacture, respectively. The remaining broken lines in FIG. 1 illustrate portions of a graphical user interface. The broken line showing of a portable information terminal in FIGS. 2-6 illustrates environmental subject matter. None of the broken lines form part of the claimed design.
